UNITED STATES PATENT OFFICE.

KATHERINE B. WOODLEY, OF OAK PARK, ILLINOIS, ASSIGNOR OF ONE-HALF TO
BERTHA BOWEN, OF CHICAGO, ILLINOIS.

RAINCOAT.

Application filed June 19, 1924. Serial No. 720,908.

To all whom it may concern:

Be it known that I, KATHERINE B. WOODLEY, a citizen of the United States of America, and a resident of Oak Park, Illinois, 5 have invented a certain new and useful Improvement in Raincoats, of which the following is a specification.

This invention relates to improvements in rain capes particularly adapted for use in 10 emergencies, and an improved process of manufacturing the same. The principal object of my invention is to produce an article of the class described which is made of relatively inexpensive material such as water- 15 proof paper and which may be formed from a simple pattern and be folded into a compact package but when in use will provide protection from rain especially in cases of emergencies and which may under ordinary 20 conditions be used several times before discarding.

My invention may be best understood by reference to accompanying drawings, in which:

25 Fig. 1 is a view of the completed cape in use.

Fig. 2 is a side view of the cape shown in Fig. 1.

30 Fig. 3 is a detailed sectional view taken transversely of the fold adjacent one of the arm holes.

Fig. 4 is a view showing the pattern from which the cape is made, and illustrating the manner in which the creping is applied 35 thereto during the process of forming the cape.

Referring now to the embodiment of my invention shown in the drawings: The cape or garment 10 consists of a body portion 11 40 having a hood portion 12 formed integrally therewith. These portions are preferably made of waterproofed paper or similar relatively inexpensive material. The body portion may be of different lengths as desired, 45 in the form illustrated in full lines a substantially $\frac{1}{2}$ length cape is shown, while the dotted lines 12^a indicate that it can readily be extended, as for instance to a $\frac{3}{4}$ length cape.

50 Referring now to the pattern from which my improved garment is made, and the method of forming the same which constitutes an important feature of the invention, a typical pattern is illustrated in Figure 4, 55 which shows a single flat piece of material.

Said material is preferably of waterproof paper, of suitable strength and texture to be readily crimped or pleated. The pattern is substantially circular in shape.

In order to produce a substantially form-fitting device as shown in Figures 1 and 2, this piece is grasped by the hand, or other suitable securing means, substantially at the center point of the material area, as for instance at B, while the outer margins are 60 brought together, and in this position the material is crimped or pleated in folds extending along lines radiating from the part B, as indicated by the lines C, C on the pattern. Any suitable means may be used to 65 produce this crimping or pleating effect, as for instance, by twisting by hand, or by pleating along more regular folds with machinery. The line 14 on the pattern indicates the line of cut for forming the hood 11. 70 I prefer to make this cut after the whole piece A is crimped so that both hood 11 and body pattern 12 will be given their desired form in one operation, and without danger of tearing the material at the juncture of 75 the hood and body portion.

Armholes 20 may be cut in form of slits as indicated. Rows of fasteners, as for instance consisting of eyelets 21-21, and strings 22-22, of the ordinary kind commonly used for fastening envelopes. These eyelets are preferably arranged along substantially lines as shown herein, two pairs of lines 23, 23 and 24, 24 being provided, each pair being on opposite sides of an armhole 80 20, the arrangement being such that the eyelets may be fastened by hand, either passed through the armholes, and fastened from the inside of the fold formed thereby, or, by passing the hand and arm around the lower 85 margin of the garment and fastening from the outside. When fastened along the lines indicated the fold illustrated in Figure 3 thus provide additional protection for the arms which may be enclosed in the fold. 90 The armholes are also thus protected against the entrance of rain. Furthermore, by use of these fasteners, the garment is made to conform more closely to the body of the wearer. 105

The garment is also capable of being further conformed to fit the wearer by means of a tape or string 25 threaded around the hood portion 12 above the cut 14 so that the hood may be fitted to the head as desired. 110

Another tape or string 26, is also threaded around the top of the cape, below the cut 14 so as to fit the same closely around the neck of the wearer.

- 5 Under some conditions it may be desired to cut out a portion of the material of the body portion along substantially radial lines, as for instance lines 29 and 30 of the pattern and then secure adjacent margins 10 of the body portions together, so as to cut out excessive fullness of the garment. Under ordinary conditions, however, and especially in case the shorter length garments are used, I find that the garment pleated or 15 crimped as described, readily conforms itself to the body of the wearer without showing any evidence of excessive material, and yet affording comfort and full freedom of movement to the wearer.
- 20 A garment constructed in accordance with my invention is capable of being made economically in large quantities and to be sold at a low figure for emergency wear. It may be folded compactly for carrying or for sale 25 in vending machines. By virtue of its crimped formation it adjusts itself readily to wide variations in sizes. Furthermore, it exhibits unusual wearing qualities and it may be readily wrung out and dried after 30 it becomes wet, thereby affording repeated use, if desired.

While I have illustrated and described one particular embodiment of our invention, it will be understood that I do not wish to be limited to the exact construction shown and described, but that various changes and modifications may be made without departing from the spirit and scope of my invention.

- 35 40 What I claim as my invention is:

1. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines radiating toward said 45 margins.

2. A garment having a body portion and a hood portion formed of one piece of waterproof paper, said piece being cut on a substantially continuously curved line to form the lower or outer margins of said body portion, and also being cut on a curved line adjacent the center of area thereof to form said hood portion, said material being crimped or folded along lines centering substantially in said hood portion and radiating toward said margins.

3. A garment having a body portion and a hood portion formed of one piece of waterproof paper, said piece being cut on a substantially continuous curved line to form the

lower or outer margins of said body portion, and also being cut on a curved line adjacent the center of area thereof to form said hood portion, said material being crimped or folded along lines centering substantially in said hood portion and radiating toward said margins, and string means threaded about the margin of said hood portion for gathering the same. 70

4. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines centering substantially to said hood portion and radiating toward said margins, and string means 80 threaded circularly below said hood portion to form a constricted opening adapted to fit the neck of the wearer. 85

5. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines centering substantially in said hood portion and radiating toward said margins, string means threaded about the margin of said hood portion for gathering the same, and string means threaded circularly below said hood portion to form a constricted opening adapted to fit the neck of the wearer. 90

6. A garment having a body portion and a hood portion formed of one piece of waterproof paper; said piece being cut on a substantially continuous curved line to form the lower or outer margins of said body portion, and also being cut on a curved line adjacent the center of area thereof to form said hood portion, said material being crimped or folded along lines radiating toward said margins, and a plurality of cooperating fastening devices on said body portion arranged in rows spaced apart on substantially radial lines. 100

7. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines radiating toward said margins, a pair of arm holes in opposite sides of said body portion, and fastening means for forming folds in said body portion, said folds including said arm holes. 115

8. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines radiating toward said margins, a pair of arm holes in opposite sides of said body portion, and a plurality of cooperating fastening devices on said body portion arranged in rows spaced apart on substantially radial lines on opposite sides of said arm holes. 35
- 5 9. A garment having a body portion and a hood portion formed of one piece of waterproof paper, said piece being cut on a substantially continuous curved line to form the lower or outer margins of said body portion, and also being cut on a curved line adjacent the center of area thereof to form said hood portion, said material being crimped or folded along lines centering substantially in said hood portion and radiating toward said margins, string means threaded about the margin of said hood portion for gathering the same, string means threaded circularly below said hood portion to form a 40
- 10 20 25 30 constricted opening adapted to fit the neck of the wearer, a pair of arm holes in op- 45
- posite sides of said body portion, and a plurality of cooperating fastening devices on said body portion arranged in rows spaced apart on substantially radial lines on opposite sides of said arm holes. 50
10. The method of forming a garment of waterproof paper which consists of cutting a pattern of flat paper material along a continuously curved line, crimping or pleat- 40
- 15 ing said material along substantially radial lines centering adjacent the center of area thereof, and thereafter cutting said material to provide hood and body portions of the 45
- garment. 55
11. The method of forming a garment of waterproof paper from a pattern of flat paper material substantially circular in shape, the center portion of which is adapted to form a hood and the surrounding material adapted to form a body portion, which consists in crimping or pleating said material in folds arranged radially of the piece, and centering in the portion of the area adapted to form said hood and thereafter cutting said material along a substantially concentric line to provide hood and body portions of the garment. 60

Signed at Chicago, Ill., this 16th day of June, 1924.

KATHERINE B. WOODLEY.
